UNITED STATES PATENT OFFICE.

JOHN BEERMAKER, OF WAHOO, NEBRASKA.

BURGLAR-PROOF CAR.

SPECIFICATION forming part of Letters Patent No. 478,554, dated July 12, 1892.

Application filed February 19, 1892. Serial No. 422,115. (No model.)

To all whom it may concern:

Be it known that I, JOHN BEERMAKER, a citizen of the United States, residing at Wahoo, in the county of Saunders and State of Nebraska, have invented a new and useful Burglar-Proof Car, of which the following is a specification.

My invention relates to burglar-proof cars for the transportation of valuables by railroad; and the objects in view are to provide a compartment adapted to be built into the end of an ordinarily-constructed express-car or cars built for the purpose, which compartment shall be burglar-proof and adapted to withstand attacks and repel shots, and, furthermore, to be so constructed as to be used as a compartment for defenders of the car during attacks by robbers and to provide for them protection against such robbers and afford them unobstructed views up and down the sides of the car and from one end of the train to the other, whereby the entrances to the several cars of the train may be covered by the rifles of the defenders.

Other objects and advantages of the invention will appear in the following description, and the novel features thereof will be particularly pointed out in the claims.

Referring to the drawings, Figure 1 is a side elevation of a burglar-proof car constructed in accordance with my invention. Fig. 2 is an end view of the car. Fig. 3 is a transverse section through the burglar-proof portion. Fig. 4 is a longitudinal section of the front portion of the car. Fig. 5 is a detail in perspective of one of the swells and frame for operating the same.

Like numerals of reference indicate like parts in all the figures of the drawings. 1 designates the side wall of an express-car, and 2 the floor, the car being of ordinary construction, with the exception that it is provided near one end with openings 3 in its side walls. Within the car the same is traversed by a metal partition 4, whereby a compartment is formed at one end of the car and opposite the openings 3. This middle partition is nothing more than a metal frame, and has hinged to its opposite edges, as at 6, metal door-sections 7, and to these are hinged, as at

8, inner metal door-sections 9. Oppositely-disposed keepers 10 are secured to the sections 7 at their inner sides, and a locking-bar 11 is pivoted, as at 12, to near one edge of one of the sections 9. It will be obvious that these door-sections may be folded, so as to open the compartment and throw the same into the interior of the car, or by closing the door-sections and locking them by means of the locking-bar 11 a rigid metal partition extends entirely across the car.

A keyhole-shaped port hole or holes 13 are formed in one of the sections 9, or in both or all of the sections 9 and 7, as may be desired, and in rear of the same pockets 14 are secured, said pockets having pivoted therein guard-plates 15, which normally cover the lower ends of the port-holes and are supported in such position by means of springs 16.

It will be seen that the metal partition will preserve the compartment against attack from the interior of the car, and that persons within the compartment and provided with firearms have a clear vision and control of the interior of the car through the port-holes.

The openings 3 in the side walls of the car are provided with what I term "swells," and each swell consists in a lower section 17, hinged at its lower edge, as at 18, to the bottom edge of the opening 3, and an upper section 19, hinged, as at 20, at its lower edge to the upper edge of the section 17. Side strips 21 extend upwardly and at an angle to the lower sections of the swells, and are provided at their upper ends with inwardly-disposed L-shaped brackets or arms 22. A U-shaped frame 23 is secured to the inner face of each of the upper sections 19, the terminals of the frame extending down and inclosing the side strips 21 of the lower section. The strips 21 and the terminals of the frame are provided at their inner faces with laterally-bent flanges 24 for engaging the side edges and upper edge of the opening 3 in the wall of the car. Keyhole-shaped ports 25 are formed in the upper section 19, and are provided with pockets at their inner sides, (indicated at 26,) and having guard-plates 27 for normally covering the ports located therein. Similar ports 28 are formed in the sides of the frames 23, and

immediately above the same in the outer corners of the frame and in the upper corners of the upper sections 19 glass-covered openings 29 are provided.

5 In the upper corners of the frames 23 boxes 30 are provided, and the same support lamps 31, the rays of which are deflected through the glass-covered light-openings, and hence light the sides of the train and opposite sides 10 of the track on which the train stands. The L-shaped brackets or arms 22 are connected by transversely-disposed reflecting-plates 33, and the same may, in a manner hereinafter described, be swung to close the boxes for 15 supporting the lamps, and hence reflect the light from the lamps through the glass-covered openings, or when the swells are closed or at their inner positions, said plates will be withdrawn from the boxes, so that the rays 20 of light from the lamps will be shed within the compartment.

A shaft 34 is mounted in bearings 35, formed in the partition-frame 4 and end wall of the car, and from the same near its ends extend 25 diametrically oppositely-disposed rock-arms 36, which rock-arms have their extremities connected by links 37 with the upper ends of the L-shaped bracket-arms 22. The shaft is also provided with an operating-lever 38, 30 by which it may be rocked.

The openings in the walls of the car have their inner faces covered by metal frames 40, and the front wall of the car is lined by a metal frame 41, and, if desired, a metal roof 35 42 (shown by dotted lines) may be provided, and a bottom 43, so that the entire chamber or compartment is surrounded by metal and adapted to withstand attacks from all sides.

In case the car is attacked or running 40 through dangerous country the rock-shaft within the car is oscillated, so that the rock-arms are brought nearly to a horizontal position, which forces the swells outwardly from the walls of the car and closing the reflecting-plates against the lamp-boxes reflects the 45 light along the sides of the entire train, so that persons looking through the ports at the sides of the swells obtain a perfect view of the entire train from the locomotive to the 50 rear car, and with rifles or other firearms can successfully command the entire train and its entrances. The bringing of the reflecting-plates against the rear sides of the lamp-boxes also darkens the car, so that the port-holes 55 cannot be seen or any object within the compartment to offer a target for the aim of the robbers. In this manner parties of robbers may be successfully repelled and the valuables contained in the express-car preserved. 60 When not in danger from an attack, the car may be given the ordinary appearance by swinging the rock-shaft to the opposite direction, so as to contract the swells into alignment with the sides of the car.

65 For the convenience of the trainmen at stations the swells can be set out and the

search-lights will light both sides of the train, so as to make all objects more visible and for the convenience of the passengers getting on or off the train.

70 My invention can be attached at any part of an express, baggage, mail, or passenger car where it can be made most convenient to suit the inside of the car.

Having described my invention, what I 75 claim is—

1. A car provided at opposite sides with openings, combined with swells hinged at their lower edges to the openings and provided at their upper corners with light-openings and lamp-supports, of means for opening and closing the swells, a reflecting-plate 80 located at the inner side of each light-lamp support, and means for throwing the same, toward or away from the light-supports, substantially as specified.

2. The combination, with the car, the opposite walls of which are provided with openings, of opposite swells hinged at their lower edges to the openings, an intermediate rock-shaft provided with rock-arms, and links connecting the rock-arms with the swells, substantially as specified.

3. The combination, with the car having the opposite openings, the hinged swell-sections having the side strips bent to engage the edges of the openings and terminating at their upper ends in arms, the upper sections hinged to the lower sections and provided at their inner edges with the U-shaped 95 frames, having their inner edges bent to engage the opening in the car, of the intermediate rock-shaft, the rock-arms on the same, and the links connecting the rock-arms with the side strips of the lower swell-sections, 100 substantially as specified.

4. The combination, with the car having the opposite openings in its side walls, of the lower swell-sections hinged at their lower edges to the openings and provided with the 110 side strips, terminating at their upper ends in inwardly-disposed L-shaped arms, the upper swell-sections having the U-shaped frames at their inner faces, embracing the side strips, the light supports and openings 115 at the upper corners of the frames, the transverse reflecting-plates mounted on the L-shaped arms, the intermediate rock-shaft, the lever for operating the same, the rock-arms extending from the shaft, and the pivoted links connecting the outer ends of the 120 rock-arms with the upper ends of the L-shaped arms of the side strips, substantially as specified.

5. The car having the opening in its side 125 wall, combined with the lower swell-section hinged to the bottom of the opening, the upper swell-section hinged to the lower section, the side pieces for the two sections terminating at their inner edges in stops, and means for opening and closing the section, 130 substantially as specified.

6. A car one end of which is provided with port-holes and in front of the same with a transverse partition-frame, the door-sections adapted to fold and hinged to the frame, the 5 reversely-disposed keepers, and the intermediate locking-bar pivoted to one of the sections, substantially as specified.

In testimony that I claim the foregoing as my own I have hereto affixed my signature in the presence of two witnesses.

JOHN BEERMAKER.
